Des. 199,027
Patented Sept. 1, 1964

199,027

TABLET ARMCHAIR

Robert W. Conde, 210 N. Washington Ave.,
Batavia, Ill.

Filed Jan. 30, 1964, Ser. No. 78,430

Term of patent 3½ years

(Cl. D33—11)

FIG. 1 is a perspective view of a tablet armchair embodying my new design;

FIG. 2 is a front elevational view thereof;

FIG. 3 is a top plan view thereof; and

FIG. 4 is a rear view thereof.

I claim:

The ornamental design for a tablet armchair, substantially as shown.
